UNITED STATES PATENT OFFICE.

LOUIS GODDU, OF WINCHESTER, MASSACHUSETTS, ASSIGNOR TO GORDON MCKAY, OF NEWPORT, RHODE ISLAND, AND JAMES W. BROOKS, OF CAMBRIDGE, MASSACHUSETTS, TRUSTEES.

NAILING-MACHINE.

SPECIFICATION forming part of Letters Patent No. 288,425, dated November 13, 1882.

Application filed September 11, 1883. (No model.)

To all whom it may concern:

Be it known that I, LOUIS GODDU, of Winchester, county of Middlesex, State of Massachusetts, have invented an Improvement in 5 Nailing-Machines, of which the following description, in connection with the accompanying drawings, is a specification, like letters on the drawings representing like parts.

This invention in nailing-machines, more especially designed for boot and shoe work, has for its object improvements in the mechanical devices for selecting the nails and placing them separately in the line of the descent of the driver.

15 My improvements are herein illustrated as applicable to a machine such as represented in United States Letters Patent No. 265,227, granted to me September 26, 1882, to which reference may be had, but may, it is obvious, 20 be applied to other nailing-machines.

Figure 1 in side elevation represents portions of a boot and shoe nailing machine such as described in the said patent, but with my present improvements added. Fig. 2 is a 25 broken detail of parts only of Fig. 1, viewing it from the right, a part of the nose and driver-bar being broken out to show the transerrer and chute-cover beyond it. Fig. 3 is a broken detail taken from the left-hand side of Fig. 1, 30 omitting the nail-feeding drum and all the chute except a small portion thereof at one end, just about enough to support one or two nails, the said figure showing most of the devices broken away from Fig. 2, some of the 35 parts shown in Fig. 2 being fully broken out from Fig. 3. Fig. 4 is a vertical nearly central section of Fig. 3, the chute being entirely omitted. Fig. 5 is an end view of the chute; Fig. 6, a side view of the delivery end of the 40 chute, and Fig. 7 an inner side view of the nose next the end of the chute.

The drum E, the chute m, its cover n, vibrating head B, nail-driver bar a, nose e, connection h between the nose and cover, the 45 stop-rods f³ f⁴, toothed sector f⁵, sleeve f⁸, spring-pressed pin f⁷, and shaft C are the same in construction and operation as those represented by the like letters of reference in the

patent referred to. The head B has two like studs or rock-shafts, a² a³, provided, respectively, with arms b b' and d d', the latter having attached to them suitable transmitters, g g', the ends 25 of which, when the transmitters are farthest in, as in Fig. 3, to close the roadways, come into line with and form part of the passage or guide way for the usual driver of the driver-bar. The two arms b b' are connected by a spring, b², which acts to normally keep the roller-studs t t' of the transmitter-levers d d' against, respectively, the two acting cam-faces e e' of the cam-hub e², fast on shaft C. In practice one of the levers d d' will be held by one of the said stop-pins f³ or f⁴, to cause the transmitter carried by it to close the end of the roadway next to it, while the other lever or its roller-stud is acted upon by the cam e or e', to cause the transmitter carried by that lever to alternately open and close the end of the roadway with which it co-operates, transferring one nail after another from the roadway 70 into the nose or its passage r. These levers d d', for moving the separators, and the rocking-levers n n', the hollow hubs of which are slipped loosely, respectively, over the shafts a² a³ referred to, are all substantially as in my application, Case A, No. 106,132, filed September 11, 1883.

The levers n n' are provided, respectively, with anti-friction rollers k k', which are normally kept pressed against the cam-surfaces h 80 h' of the cam-hub e² by the connecting-spring m².

The levers n n' are provided, respectively, with separators o o', (the one o' Fig. 3, being best shown,) which operate in like manner in connection with a roadway of the chute, each 85 effecting the separation of nails singly from the ends of the roadways and delivering them to the transmitters, as in my said application. Only the roadway marked 2 is shown in Figs. 2 and 3. These separators enter between the 90 endmost nail and the one next to it, closing the raceway and chute, while the transmitter removes a nail from the end of the roadway of the chute into position substantially at the center line of the nose in line with the driver- 95 passage r.

The face of the end of the chute *m* is shown in Fig. 5, its side in Fig. 6.

The open ends of the roadways are inclined or made V-shaped with relation to each other, 5 thereby causing the points of the nails to be carried in toward the line of the driver-passage in the nose, and to keep the nails from falling down or hanging straight by gravity, I have provided the inner side of the nose 10 (see Fig. 7) with two nail-rests, *p p'*, the inner faces, 15, of which are set at the same inclination as the delivery ends of the roadways, so that the separators crowd the nails, one at a time, from the roadways and leave them lying 15 on the said rests.

Each nail-rest *p p'* is connected with a stem, *q*, extended transversely through the nose and notched at its outer end for the reception of one end of a suitable spring, *s*, (see Figs. 1 20 and 2,) shown as a forked steel plate fastened to the outer side of the nose *c* by a screw, *s'*, the said spring acting to keep the nail-supports *p p'* pressed against the end of the chute, the face 15 of each support *p* being in line 25 with the wall of the roadway of the chute and filling the small space between the end of the chute and the side of the nose, and the nail removed from the roadway of the chute is supported, as stated, upon the face 15 of the rest.

30 The end of the rest next the end of the chute is slightly beveled for the entrance between it

and the said chute of the beveled edge 14 of the transerrer, and at such time the nail-support *p* is pressed back into a recess, *p'*, in the nose against the action of the co-operating 35 spring *s*, so that the nail which rested against the part 15 of the support may be moved forward into the driver-passage *r* of the nose *c* by the transerrer.

The chute has two roadways for nails of different lengths, and those of either length may be used in the nose at will by causing one or the other transerrer and its separator to work, and keeping the opposing separator and transerrer inactive. 40

I claim—

The chute and the nose provided with the driver-passage, and the spring-held nail-support placed in the nose and pressed toward the end of the chute and adapted to receive a 50 nail upon it, combined with a transerrer to move the said nail into the line of the driver-passage, the supporter being at such time moved backward, substantially as described.

In testimony whereof I have signed my name 55 to this specification in the presence of two subscribing witnesses.

LOUIS GODDU.
